UNITED STATES PATENT OFFICE.

ARNOLD STUCKI, OF ALLEGHENY, PENNSYLVANIA.

CAR-COUPING.

No. 831,249.

Specification of Letters Patent.

Patented Sept. 18, 1906.

Application filed August 31, 1905. Serial No. 276,603.

To all whom it may concern:

Be it known that I, ARNOLD STUCKI, a resident of Allegheny, in the county of Allegheny and State of Pennsylvania, have invented a new and useful Improvement in Car-Couplers; and I do hereby declare the following to be a full, clear, and exact description thereof.

This invention relates to car-couplers of the automatic type; and the object is to provide a coupler provided with knuckle-locking means so arranged that it cannot creep or jump up under the jolting of the car and accidentally unlock the knuckle, which can be set in unlocked position, so that it need not be held by the brakeman even though the cars do not immediately pull apart, which will be dislodged from said set position when the knuckle swings open, and which is also arranged to throw open the knuckle.

The invention consists in the special construction and arrangement of parts herein-after described and claimed.

In the accompanying drawings, Figure 1 is a plan view of my improved coupler, showing the knuckle in unlocked position. Fig. 2 is a horizontal section of the companion coupler, taken on the line 2 2, Fig. 4, and showing the knuckle in locked position. Fig. 3 is a similar view taken on the line 3 3, Fig. 4, and showing the knuckle in unlocked position. Fig. 4 is a vertical longitudinal section on the line 4 4, Fig. 1, showing the locking-block in locking position. Fig. 5 is a similar view showing the locking-block in unlocked set position. Fig. 6 is a similar view showing the locking-block at its extreme upper position. Fig. 7 is a horizontal section on the line 7 7, Fig. 5. Fig. 8 is a view looking upwardly into the recessed head, and Figs. 9 and 10 are perspective views of the locking-block.

My invention may be applied to any automatic car-coupler having a pivoted or swinging knuckle. It comprises a suitable head 1, having therein a recess or chamber 2 and provided with lugs 3, between which the knuckle 4 is pivoted by means of the pin 5. The head is also provided with the horn 6, as is common in this type of couplers, and with the shank 7 for attachment to the draft mechanism.

The knuckle is provided with a tail 8, which projects back into the recess 2 of the head and which at its end is provided with the hook 9 for engaging a lug or similar means 10 on the head, so as to prevent the

knuckle from pulling out even though the pivot-pin 5 should become broken or lost. The outer end of the knuckle-tail is curved or rounded, as shown at 11, and abuts when locked against the wall of the head, as shown in Fig. 2, so as to take the buffing strains off the pin 5. Said tail has a flat face 12 for bearing against the locking-block.

The locking-block 13 forms the special feature of this invention. This block is substantially rectangular in horizontal cross-section and its long axis is preferably arranged transversely of the coupler-head, as shown. It has its upper front corner cut away, as shown at 14, and on its top is provided with beveled or inclined faces 15 and 16, which are oppositely arranged. Projecting out from one side of the block is the arm 17, which serves to throw the knuckle open. On its lower face the block is provided with a pin or prong 18, which extends down through a hole 19 in the floor 20 of the head. The upper portion of this pin is substantially triangular in cross-section and is provided with a curved face 21, against which the end of the knuckle-tail will contact when the knuckle swings open. The lower part of this pin or prong is round, as shown at 22. The lifting-chain, link, or rod 23 is attached to the block eccentrically, being shown as located in front of the center of gravity of said block. The hole 19 in the floor of the head is in the form of a slot, lying longitudinally of or parallel with the axis of the coupler. The floor of said head is higher at the rear of said slot at 24 than it is at the front end of said slot. The recess in the head is provided with suitable guides 25 for guiding the block vertically and at its upper portion is provided with oppositely-inclined faces 26 and 27, which serve to rotate the block on its vertical axis. The wall at the front of the recess is provided with an inwardly-projecting lug, shoulder, or ledge 28, which lies substantially in the plane of the top of the block when in its locking position.

The knuckle-tail is provided with the vertical face 29, against which the end of the arm 17 bears when throwing the knuckle open. This arm projects upwardly and then curves downwardly and in the locked position of the parts lies in a cavity 30, formed in the tail of the knuckle, this being done merely to save space. When the knuckle is locked, the hook 9 on its tail will engage the lug 10 on the coupler-head, the locking-block 13

will be in its lowermost position with one end in position to receive the thrust of the face 12 on the knuckle-tail, and its opposite end bearing against the wall 31 of the head-recess. The block, therefore, has a solid thrust-bearing on the side opposite to the knuckle-tail, so that it is impossible to break or bend said block. The arm 17 projects above the tail, and its outer end 32 projects down into the cavity 28 of the knuckle-tail. The block 13 will rest upon the floor 20 of the head, and since the rear part of the floor is higher, as at 24, this block will be supported only at its rear edge, and consequently will tip forward by gravity. This will bring its upper front edge underneath the ledge 28, and as a consequence if said block should jump or creep upwardly under the jolting of the car it will merely strike against this ledge and cannot accidentally unlock the knuckle. When the knuckle is raised by means of the lifting-chain 23, the first effect is to swing said block on its transverse horizontal axis, thus straightening same and withdrawing its front upper edge from underneath ledge 28. Then said block will move vertically until it clears or releases the tail of the knuckle and its lower edge is above the ledge 28. Inasmuch as the lifting means is attached eccentrically to the block, said block will swing so that its front edge will be over the ledge 28. Consequently, if the cars are jammed tight together the brakeman need not hold the operating-lever until the cars pull apart, but can at once release the lever and leave his position. The block will merely fall by gravity until its forward bottom edge rests on ledge 28, thus being in "lock-set" position. When the cars pull apart, the tail of the knuckle will swing out underneath the block and the curved end 11 thereof will bear against the curved face 21 on the prong or pin 18, thus shoving the same backwardly sufficiently to dislodge the block from the ledge 28, and said block will then drop by gravity and rest upon the end of the knuckle-tail. Consequently, when the tail again swings inwardly when coupling the cars the block will be free to fall by gravity to locking position. If the knuckle has swung open before the brakeman releases the operating-handle, the knuckle-tail will bear against the prong 18 and hold it so far back that when the block drops it will not strike the ledge 28, but will come to rest on the tail of the knuckle. Consequently, when the knuckle swings to locked position the block will drop by gravity to lock said knuckle and will automatically tip forwardly, so that its front edge will come underneath the ledge 28.

The block moves substantially vertically to a height somewhat greater than necessary to release the knuckle-tail. At its extreme upper movement the inclined faces 15 and 16 on the upper side of said block contact with

the oppositely-inclined faces 26 and 27 on the walls of the head-recess. As a consequence said block will be given a rotary movement on its vertical axis, the direction of this movement being such as to swing the arms 17 around, so that its end will engage the face 29 on the knuckle and swing the same open. It will be observed that this knuckle-throwing movement of the locking-block does not occur until the knuckle is fully released, so that unnecessary friction is avoided. The block, however, is given sufficient rotary movement to throw the knuckle entirely open.

The locking-block has the following movements: first, a forward tipping movement on its rear edge to come under the ledge 28; second, a vertical sliding movement; third, a reverse swinging movement on its horizontal transverse axis due to the eccentric connection of the lifting means to the block, and the fourth, a rotary motion on its vertical axis occasioned by the oppositely-inclined faces on the roof-walls and upper face of the block. The pin or prong 18, projecting through the slot 19 in the floor, guides and steadies the block during these movements, permits said block to swing on its transverse horizontal axis, merely riding along one of the walls of the slot. Its rounded lower end serves practically as a pivot to steady the rotary movement of the block, and said prong also prevents movement of the block transversely in the coupler-head.

While both the block and the roof of the head are shown as provided with oppositely-inclined faces, this is merely to prevent friction. It would be sufficient if one member only had such faces, and, indeed, a spiral groove or rib on one member engaging a lug on the other would answer the purpose.

It is obvious that many changes may be made in the details of construction of this coupler without departing from the spirit of my invention. It is extremely simple and cannot get out of order. The means of unlocking and opening the knuckle, together with the lock-set feature, is all accomplished by the use of a one-piece block, thus greatly simplifying the device and rendering it less liable to derangement.

What I claim is—

1. In a car-coupler, the combination of a head, a knuckle pivoted thereto, said head having a solid wall directly opposite the knuckle-tail when the latter is in locked position, and a single-piece locking-block in the head having plane lateral faces and being wide and low and of such dimensions laterally of the head as to fill the space between the knuckle-tail and the solid wall of the head to transmit the unlocking thrust of the knuckle-tail directly to the said wall, said block being arranged for a vertical unlocking movement and a gravity-controlled swinging move-

- ment on its transverse horizontal axis for the purpose of locking said block against accidental upward movement.
2. In a car-coupler, the combination of a head, a knuckle pivoted thereto, said head having a solid wall directly opposite the knuckle-tail when the latter is in locked position, and a single-piece locking-block in the head having plane lateral faces and being wide and low and of such dimensions laterally of the head as to fill the spaces between the knuckle-tail and the solid wall of the head to transmit the unlocking thrust of the tail directly to said wall, the arrangement being such that when in its locked position one edge of said block is supported while the opposite edge is unsupported, whereby the block will tip and bring said edge underneath a projection of the head.
3. In a car-coupler, the combination of a head, a knuckle pivoted thereto, said head having a solid wall directly opposite the knuckle-tail when the latter is in locked position, and a single-piece locking-block in the head having plane lateral faces one of which bears against the knuckle-tail and the other against the solid wall of the head, said block being wide and low and transmitting the unlocking thrust of the tail directly to said solid wall and being so arranged that in its locking position its rear edge rests on the floor of the head, thus causing said block to tip and bring its forward edge underneath a projection on the head.
4. In a car-coupler, the combination of a head, a knuckle pivoted thereto, said head having a solid wall directly opposite the knuckle when the latter is in locked position, and a solid locking-block in said head having plane lateral faces one bearing against the knuckle-tail and the other against said solid wall whereby said block transmits the unlocking thrust of the knuckle-tail directly to said wall, said block being arranged to have a gravity controlled and guided vertical unlocking movement and a subsequent swinging movement on its horizontal transverse axis for the purpose of setting said block in unlocked position.
5. In a car-coupler, the combination of a recessed head provided with a projection at the forward portion of its recess, a knuckle pivoted to said head, a knuckle-locking block in said head and arranged for a gravity controlled and guided vertical unlocking movement, and a lifting device attached to said block in front of its center of gravity, whereby when the block is raised it will swing to bring it above the projection on the head.
6. In a car-coupler, the combination of a head, a knuckle pivoted thereto, said head having a solid wall directly opposite the knuckle-tail when the latter is in locked position, and a solid locking-block in said head having plane lateral faces one of which bears

against the knuckle-tail and the other against said solid wall whereby said block transmits the unlocking thrust of the knuckle-tail directly to said wall, said block being arranged for a gravity controlled and guided vertical unlocking movement and for swinging movements on its transverse horizontal axis for the purpose of both locking the same against accidental upward movement and for setting the same in unlocked position.

7. In a car-coupler, the combination of a recessed head provided with an inward projection and with a solid wall opposite the knuckle-tail when the latter is in locked position, a knuckle pivoted to said head, a single-piece knuckle-locking block in said head having plane lateral faces one of which bears against the knuckle-tail and the other against the solid wall of the head and thereby transmits the unlocking thrust of the tail directly to said head, said block being arranged for a gravity controlled and guided vertical unlocking movement, the block and head being so arranged that when the former is in its locking position it will be supported at one edge and unsupported at the opposite edge, whereby it will tip to bring the latter edge underneath the projection of the head, and a lifting device attached to said block eccentrically, whereby when lifted the block will swing so as to come above the projection on said head.

8. In a car-coupler, the combination of a recessed head provided with an inwardly-projecting portion on its front wall and with a solid wall opposite the knuckle-tail when the latter is in locked position, a knuckle pivoted to said head, a knuckle-locking block in said head having plane lateral faces one of which bears against the knuckle-tail and the other against the solid wall of the head and thereby transmits the thrust of the knuckle-tail directly to said wall, said block being arranged for a gravity controlled and guided vertical unlocking movement, said head and block being so arranged that in its unlocking position the block is supported at its rear edge only, thereby causing the same to tip and bring a portion thereof underneath the projection on the head, and a lifting device attached to said block in front of its center of gravity, whereby when said block is lifted it will swing above the projection on said head.

9. In a car-coupler, the combination of a recessed head provided with an inward projection and with a solid wall directly opposite the knuckle-tail when the latter is in locked position, a knuckle pivoted in said head, a knuckle-locking block in the head arranged for vertical unlocking movement and having plane lateral faces one of which bears against the knuckle-tail and the other against the solid wall of the head, thereby transmitting

the unlocking thrust of the knuckle-tail directly to said wall, a lifting device attached to said block eccentrically, whereby the block will tip and rest upon the projection in 5 said head, and a straight guiding-prong on the block adapted to be hit by the tail of the knuckle when swinging open to dislodge said block.

10. In a car-coupler, the combination of a 10 recessed head provided with a projection and with a solid wall directly opposite the knuckle-tail when the latter is in locked position, a knuckle pivoted in said head, a single-piece locking-block in said head having 15 plane lateral faces one of which bears against the knuckle-tail and the other against the solid wall of the head and transmits the unlocking thrust of the knuckle-tail directly to said wall, said block being arranged for a 20 vertical unlocking movement, and for a subsequent gravity-controlled swinging movement on a horizontal axis to bring the same above the projection in the head, a prong on said block passing through a slot 25 in the floor of the head and guiding the block in its swinging movement and being arranged to be struck by the tail of the knuckle in swinging open to dislodge said block.

11. In a car-coupler, the combination of a 30 head, a knuckle pivoted thereto, a knuckle-locking block in said head arranged for an initial vertical unlocking movement, and a subsequent rotary movement on its vertical axis, and an arm integral with said block arranged 35 to engage the knuckle and throw the same open when the block rotates.

12. In a car-coupler, the combination of a head, a knuckle pivoted thereto, a knuckle-locking block in said head and arranged for 40 vertical unlocking movement, and oppositely-inclined faces on the head of the block arranged to rotate said block to throw the knuckle open.

13. In a car-coupler, the combination of a 45 head, a knuckle pivoted thereto, a knuckle-locking block in said head and arranged for vertical unlocking movement, and oppositely-inclined faces adapted to come into play at the upper end of the movement of the block 50 and rotate the same on its vertical axis, said block being provided with means for engaging the knuckle and throw it open.

14. In a car-coupler, the combination of a recessed head, a knuckle pivoted thereto, a 55 locking-block in said head and arranged for vertical unlocking movement, and a swinging motion on its transverse horizontal axis for locking the same against accidental upward movement, and a rotary movement on its vertical axis for throwing the knuckle open.

15. In a car-coupler, the combination of a recessed head provided with an inwardly-projecting portion, a knuckle pivoted in said head, a locking-block in said head, the block

and head being so arranged that when the 65 block is in its locking position it will be supported at one edge only, thus causing it to tip and bring its opposite edge underneath the projection in the head, said block being arranged to have a vertical unlocking movement, and oppositely-inclined faces arranged 70 to subsequently come into action and rotate said block on its vertical axis, to throw the knuckle open.

16. In a car-coupler, the combination of a 75 recessed head provided with an inwardly-projecting portion, a knuckle pivoted in said head, a locking-block in said head arranged for vertical unlocking movement and subsequent swinging movement on its horizontal 80 axis to bring the same above said projection, and subsequent rotary movement on its vertical axis to throw the knuckle open.

17. In a car-coupler, the combination of a 85 head provided with an inwardly-projecting portion, a knuckle pivoted in said head, a locking-block in said head, arranged for vertical unlocking movement, a lifting device attached to said block eccentrically, whereby the block will be caused to tip and swing over 90 the projection on the head, and oppositely-arranged inclined faces adapted in the further upward movement of the block to come into play and rotate said block on its vertical axis to throw the knuckle open. 95

18. In a car-coupler, the combination of a recessed head, a knuckle pivoted thereto, a locking-block in said head and arranged when in its locked position to tip on a horizontal axis to lock the block against accidental upward movement, said block being arranged for a vertical unlocking movement, a subsequent swinging motion on its horizontal axis to set said block in unlocked position, and a subsequently rotary movement on its 100 vertical axis to throw the knuckle open.

19. In a car-coupler, the combination of a recessed head provided with an inwardly-projecting shoulder or ledge, a knuckle pivoted in said head, a locking-block in said head, 110 said head and block being arranged that when the latter is in its locking position, it will be supported on one edge only, thus swinging its opposite edge underneath said shoulder or ledge, said block being arranged 115 for vertical unlocking movement and having a lifting device attached thereto eccentrically, whereby it will swing and bring a portion thereof above said shoulder or ledge, and oppositely-inclined faces arranged to subsequently come into action and swing said block on a vertical axis to throw the knuckle open. 120

20. A locking-block for car-couplers provided with a prong adapted to project 125 through a slot in the floor of the draw-head, said prong having a cam-face for the engagement of the tail of the knuckle, and with a

lower rounded portion to permit the block to rotate.

21. A locking-block for car-couplers having oppositely-inclined faces for engaging the walls of the head to cause the block to rotate, and having a downwardly-projecting prong guided in an opening in the coupler-head.

In testimony whereof I, the said ARNOLD STUCKI, have hereunto set my hand.

ARNOLD STUCKI.
